UNITED STATES PATENT OFFICE

161,619

DOLL

Myrtle R. Fry, Salina, Kans., assignor of one-half
to Barton L. Fry, Salina, Kans.

Application June 16, 1950, Serial No. 10,575

Term of patent 14 years

(Cl. D34—4)

To all whom it may concern:

Be it known that I, Myrtle R. Fry, a citizen of the United States, residing at Salina, in the county of Saline and State of Kansas, have invented a new, original, and ornamental Design for a Doll, of which the following is a specification, reference being had to the accompanying drawing, forming part thereof.

Figure 1 is a front elevational view of a doll, showing my new design; and

Figure 2 is a side elevational view of the same.

I claim:

The ornamental design for a doll, as shown.
MYRTLE R. FRY.
